MICRORAY TRANSMISSION LINE

Andre G. Clavier, Glen Ridge, N. J., assignor to International Communications Laboratories, Inc., Newark, N. J., a corporation of New York

Application December 15, 1931, Serial No. 581,147

10 Claims. (Cl. 178—44)

This invention relates to micro-ray transmission lines, that is, transmission lines for signaling systems in which micro-rays are used. These rays may be defined roughly as the electromagnetic waves the length of which lies between the limits of 100 centimeters and one centimeter, although these limits may be exceeded in either direction.

In U. S. Patent No. 1,928,408 I have disclosed apparatus for the transmission and reception of waves in this range. In that application I have also disclosed a transmission line between the antenna and the micro-ray tube which consists of concentric conductors. It is desirable that a portion of this line shall have a small characteristic impedance for maximum transfer of energy. For this portion to have a small characteristic impedance, it is necessary that the ratio of the inside diameter of the external conductor to the outside diameter of the internal conductor be small, not exceeding approximately 1:3.

My investigations have also disclosed the fact that it is desirable for the leads to the oscillating electrode, both inside and outside the tube, be parallel for their entire length. In the U. S. patent above-referred to, it is disclosed that a portion of the concentric transmission line may be a quarter-wave length long to act as a transformer and permit the internal impedance of the tube to match the impedance of the radiating system. This quarter-wave length section is most conveniently connected directly to the leads from the oscillating electrode.

The object of this invention is to provide means for connecting the leads from the oscillating electrode to the concentric conductors in such a manner that the leads may be parallel, the concentric transmission line may have a low characteristic impedance, and also the dimensions of the external concentric conductor may be kept small.

In the drawing,

Fig. 1 is a diagrammatical sketch, partly in section, of a micro-ray tube, with the leads therefrom connected to two concentric conductors and the concentric conductors connected to a radiating system; and

Fig. 2 is a diagrammatical sketch showing how such a system may be most conveniently connected to a thermocouple and galvanometer.

In Fig. 1 a micro-ray tube 1 has a cathode 2, an oscillating electrode 3, and a reflecting electrode 4. In the tube 1 of the type employed by applicant, it has been found that the plate or reflecting electrode 4 repels the electrons projected toward it from the cathode 2, and these repelled electrons

set up differences of potential along the length of the grid or oscillating electrode 3. These differences of potential, in turn, cause a variation in the electronic discharge taking place between the cathode 2 and the plate 4 and thus produce oscillations in the tube 1. As the action of the plate 4 is analogous to the phenomena of reflection, it has seemed desirable to term the plate the reflecting electrode, and in view of the differences of potential set up along the length of the grid 3, it has seemed desirable to term this element the oscillating electrode. Leads 5, 6 are connected to the ends of the oscillating electrode. As above stated, distributed potential difference is set up along the length of the oscillating electrode 3, and as the ends of this electrode constitute points of maximum potential difference, it is obviously desirable, in order to transfer to the transmission line the high frequency E. M. F. thus built up, to connect the leads 5 and 6 to the ends of this electrode. A concentric transmission line, consisting of an outer cylindrical conductor 7 and an inner cylindrical conductor 8, are shown connected to the leads 5, 6. The lead 5 is connected to a point 9 on the outer conductor and the lead 6 is connected to a point 10 on the inner conductor exactly opposite point 9. That is, the points 9 and 10 lie on a line which divides the two conductors into two equal sections. The connections to these conductors may be made by drilling a small hole in each of them, inserting an end of the lead wire in the hole, and securing it therein with solder. In order to make this connection more easily, an extra thickness of metal can be fixed at points 9 and 10, as shown in the drawing, the first one outside the outer tube and the other one inside the inner tube, without introducing any electrical disturbance in the transmission system. The requirement that the leads connecting the tube and the concentric transmission line be kept parallel is thus fulfilled by the type of connection above described.

In Fig. 2 a concentric transmission line section 11 is shown adjacent a concentric transmission line section 14 having a larger cross-section. As the radius of the outer conductor in the section 11 is less than the radius of the outer conductor in the section 14, it is evidently impossible to make the same type of connection between these two transmission line sections as was made between the oscillating electrode 3 of the tube 1 and the associated concentric transmission line. It has been found, however, that without changing the transmission characteristics of the transmission line as a whole the outer conductor of

the first concentric transmission line section 11 can be connected indifferently to either the outer or the inner conductor of the second transmission line section 14, provided that the inner conductor of the first transmission line section is connected to the remaining conductor of the second transmission line section. Accordingly, a so-called cross-over connection is made between the transmission line sections 11 and 14, that is, the 10 lead 12 connects the outer conductor of section 11 to the inner conductor of section 14, while the lead 13 connects the inner conductor of section 11 to the outer conductor of section 14.

This cross-over type of connection, of course, 15 might be used in connecting a tube as 1 to an associated transmission line of the type shown in Fig. 1 whenever the radius of the outer conductor of the transmission line is greater than the distance separating the leads as 5 and 6 connected 20 to the opposite ends of the oscillating electrode 3 of the tube 1. It is to be noted that the leads 12 and 13 are parallel in this type of connection.

This cross-over type of connection has a further advantage in that it permits the high frequency current of a sectional transmission line of the type shown in Fig. 2 to be readily measured by means disclosed in U. S. Patents 1,921,117 and 1,923,916. In these applications a wavemeter and a field strength measuring device for 30 ultra-short waves are respectively disclosed; a thermocouple and a galvanometer being used to measure the currents in a concentric conductor. One of the most convenient methods of measuring the characteristics of a transmission line is 35 to connect the thermocouple to one end of the concentric transmission line and to connect a galvanometer between the outer and inner conductors of the line. The thermal E. M. F. set up by the thermocouple in accordance with the 40 high frequency current of the transmission line then controls the galvanometer.

In connecting the thermocouple to the concentric transmission line, it is desirable that the leads extending to the thermocouple be parallel. 45 Accordingly, the thermocouple T is shown connected to the end of the transmission line section 14 by the leads 15 and 16 in the same manner that the tube 1 in Fig. 1 is shown connected to the associated transmission line.

50 For mechanical reasons it is obviously desirable to be able to connect the galvanometer to the outer conductors of the transmission line sections 11 and 14, though of course it is necessary that the galvanometer be connected between the outer and inner conductors of the transmission line. In accordance with the arrangement of Fig. 2, this is readily accomplished because of the cross-over connection above mentioned, for, by connecting one side of the galvanometer to the 55 outer conductor of the transmission line section 14, which is connected to the inner conductor of the transmission line section 11, and connecting the other end of the galvanometer to the outer conductor of the transmission line section 11, which is connected to the inner conductor of the 60 transmission line section 14, the required connections for the galvanometer can be readily made.

After these connections have been made, the 70 thermocouple T sets up a thermal E. M. F. proportional to the high frequency current in the transmission line, and this E. M. F. causes a proportional deflection of the galvanometer in a manner which is explained in the above-mentioned 75 patents, with a resulting indication of

the high frequency current in the transmission line.

It is evident that the galvanometer connections can be made at any point on the outer tubes 80 of the transmission line sections 11 and 14 without introducing any disturbances in the propagation of the high frequency current.

What is claimed is:

1. In a micro-ray signalling system, a pair of 85 parallel non-concentric leads and a transmission line consisting of concentric outer and inner conductors, one lead being connected to a point on the outer conductor, and the other lead being connected to a point on the inner conductor, both of said points of connection lying in a diameter 90 of the outer conductor but being on opposite sides of the center of said diameter.

2. The combination of a micro vacuum tube 95 having an oscillating electrode therein, leads parallel to one another connected to opposite ends of said oscillating electrode, and a transmission line consisting of concentric outer and inner conductors, one lead being connected to a point on the outer conductor and the other lead being connected to a point on the inner conductor, both of 100 said points of connection lying in a diameter of the outer conductor but being on opposite sides of the center of said diameter.

3. A measuring system for micro-rays comprising first and second sections of a transmission 105 line, each consisting of concentric outer and inner conductors, cross-over connections at adjacent ends of said sections between the outer and inner conductors thereof, a thermocouple, connections between said thermocouple and the 110 outer and inner conductors of said second section at points lying in a diameter of said outer conductor, a galvanometer, and connections between said galvanometer and the outer conductors of 115 said sections.

4. A micro-ray transmission line consisting of 120 first and second sections, each comprising concentric outer and inner conductors, a pair of parallel leads, corresponding ends of said leads being connected to points on the outer and inner conductors at adjacent ends of said first and second sections, the points of connection on the first section lying in a diameter of the outer conductor thereof, one point lying at an extremity 125 of said diameter and the other point at substantially the center of said diameter, and the point of connection on said second section lying in a diameter of the outer conductor thereof but on the same side of the center of said diameter, a thermocouple, and leads from said thermocouple 130 connected to the inner and outer conductors of said second section at points of connection lying in the diameter of said outer conductor.

5. In a micro-ray signalling system, a pair of 135 parallel non-concentric leads, and a transmission line consisting of concentric outer and inner conductors, one lead being connected to a point on the outer conductor and the other lead being connected to a point on the inner conductor, both of 140 said points of connection lying in a diameter of the outer conductor.

6. In a micro-ray signalling system, a pair of 145 parallel non-concentric leads and a transmission line consisting of concentric outer and inner conductors, one lead being connected to a point on the outer conductor and the other lead being connected to a point on the inner conductor, both of 150 said points of connection lying in a diameter of the outer conductor and on the same side of the center of said diameter.

7. In a micro-ray signalling system, a pair of parallel leads and a pair of transmission line sections, each consisting of concentric outer and inner conductors, one of said sections having a 5 larger cross-section than the other, corresponding ends of said leads being connected at adjacent ends of said sections to points on the outer and inner conductors thereof, the points of connection on each of said sections lying in a diameter 10 of the outer conductors of said sections.

8. In a micro-ray signalling system, a pair of parallel leads and a pair of transmission line sections, each consisting of concentric outer and inner conductors, one of said sections having a 15 larger cross-section than the other, corresponding ends of said leads being connected at adjacent ends of said sections to points on the outer and inner conductors of said sections, the points of connection on the smaller section lying in a diameter 20 of the outer conductor thereof, one point being at an extremity of said diameter and the other at substantially the center of said diameter,

and the points of connection on the larger section lying in a diameter of the outer conductor thereof but on the same side of the center of said diameter.

9. In a micro-ray signalling system, the combination of a transmission line consisting of inner and outer co-axial conductors, and a pair of non-concentric parallel leads connected to the respective conductors at points thereon located in a plane containing the common axis of said conductors. 80

10. In a micro-ray signalling system, the combination of a transmission line consisting of inner and outer conductors so relatively positioned that the axes thereof lie in a plane which divides the respective conductors into two equal sections, and a pair of non-concentric parallel leads connected to the respective conductors at points thereon located in said plane. 85 90
